UNITED STATES PATENT OFFICE.

HECTOR P. MACLAGAN, OF CHICAGO, ILLINOIS, ASSIGNOR TO MCINTOSH ELECTRICAL CORPORATION, OF CHICAGO, ILLINOIS, A CORPORATION OF DELAWARE.

FOOT SWITCH.

Application filed May 25, 1923. Serial No. 641,379.

My invention relates to an improved form of foot switch for controlling desired electric circuits, particularly high tension circuits used in electro-therapeutic work.

- 5 In many instances of the use of the electric current it is desirable to control the same by means of a foot switch leaving the hands of the operator free to direct the operation of the apparatus, and in such cases it frequently happens that it is desirable to be able to effect two conditions of application of the electric current, first a condition by which the current is supplied to the operated apparatus synchronously with movement or 15 pressure of the foot, so that the current is applied by pressure of the foot against the switch and interrupted when the pressure of the foot is released, and second a continuous application of the current upon a 20 pressure of the foot against the switch whether the pressure of the foot is continued or not, in which latter case a subsequent and different operation of the switch by the foot is required to interrupt the current flow. 25 This is particularly the case in connection with the application of electric current of various modalities for electro-therapeutic purposes. For convenience in the remaining description of the present invention the 30 two different conditions of application of the current will be referred to as momentary and continuous applications respectively.

By my invention I provide a foot switch convenient for operation by the foot in either one of two ways, first by a pressure on one part of the switch, contacts of the switch are operated for momentary application and second by pressure on a second part of the switch, contacts of the switch 35 are operated for continuous application; in the latter case I find it convenient to interrupt the continuous application by pressure on the part of the switch securing momentary application; the two controls referred 40 to are secured by a conformation of the switch contacts themselves such that the contacts operative for momentary application do not retain the moving parts in their operated position, whereas the contacts for 45 continuous application retain the moving parts in their operated position, thus maintaining the closure of the circuit until the operating mechanism is actuated to release the retained contacts. In carrying out my 50 invention I find it convenient to secure the

two operations referred to, by means of a single treadle operated in a first direction for momentary application and in a second direction for continuous application. My invention generically therefor consists of a 60 foot operated switch having contacts effecting momentary application for motion in one direction of the actuating mechanism and continuous application for motion in a second direction of the actuating mechanism. 65

By my invention I preferably locate the treadle portion of the actuating mechanism at a substantial distance from the switch contacts and connect the treadle mechanism 70 with the switch contacts by means of an insulating member which is desirable for high tension electro-therapeutic work to insure that the operator will not be affected by the high voltage or high frequency current employed. 75

My invention will best be understood by reference to the accompanying drawings showing a preferred embodiment thereof, in which—

80 Fig. 1 shows my improved switching mechanism in plan view with the casing partly broken away to more clearly show the arrangement of the switch contacts,

Fig. 2 is a sectional view of the parts 85 shown in Fig. 1 taken along the line 2—2,

Fig. 3 is a sectional view of the parts shown in Fig. 1 taken along the line 3—3, and

Fig. 4 is a sectional view of the contact 90 mechanism shown in Fig. 1 taken along the line 4—4.

Similar numerals refer to similar parts throughout the several views.

95 As shown in the drawings, my switch construction consists of a base 10 preferably of insulating material, for example slate, from which two supporting posts 11 and 12 project upwardly to pivotally support lugs 13 and 14 respectively. The lug 13 projects downwardly from a treadle 15 provided with two laterally extending portions 15^a and 15^b, projecting in opposite directions from the center line of the treadle. The lug 14 projects downwardly from and is rigidly secured to a plate 16, preferably of metal, and the plate 16 and the treadle 15 are rigidly connected by a bar 17 of insulating material, for example hard rubber or the equivalent, so 100 that the treadle and all of the metal parts 105 110

associated therewith are preferably at a considerable distance from the metal plate 16. The plate 16, bar 17 and treadle 15 thus form a rocking structure which may be 5 tilted in one direction by downward pressure on the extension 15^a of the treadle and in the opposite direction by downward pressure on the extension 15^b of the treadle.

The plate 16 is preferably rectangular and 10 under its edge portions the base 10 supports a first pair of contacts 18, 18^a on one side of the axis through the pivotal supports referred to, and a second pair of contacts 19, 19^a on the other side of said axis. Said 15 contacts project upwardly from the base and are rigidly secured thereto, the contacts 18 and 19^a being electrically connected by a conductor 20 and the contacts 18^a and 19 being connected by an electrical conductor 21 insulated from the conductor 20. The contact 20 is connected with one conductor 21 of the circuit controlled by the switch and the contact 19 is connected with the other conductor 22 of said circuit. As a result of the 25 construction last described, electrically connecting either the contacts 18 and 18^a or 19 and 19^a serves to electrically connect the conductors 21 and 22 extending to the circuit controlled by the switch.

The plate 16 carries on its lower surface 30 over the ends of the contacts 18 and 18^a, a contact plate 23, which as more clearly shown in Fig. 2, is pivotally supported at its mid-portion from the plate 16 and which, 35 when the extension 15^a is depressed, makes electrical connection between the contacts 18 and 18^a. This insures that the plate 23 will make contact with both of the contacts 18 and 18^a when the corresponding edge of the 40 plate 16 is depressed. The plate 16 also has extending from its lower surface above the ends of the contacts 19 and 19^a two switch blades 24, 24^a arranged to enter the upper split ends of the jaw contacts 19 and 19^a 45 which engage and by their spring action retain the blades 24, 24^a when the extension 15^b of the treadle is depressed.

A bent flat spring 25 is located between 50 the treadle 15 and the base 10, which is effective to hold the treadle 15 and plate 16 in substantially parallel relation with the base 10 when pressure is exerted upon neither of the extensions 15^a or 15^b. The tension on the spring 25 is sufficient to move the plate 16 55 and the treadle 15 to horizontal position after depression of the extension 15^a, thus moving the contact plate 23 from engagement with the contacts 18, 18^a and opening the circuit, but it is insufficient to move the 60 blades 24 and 24^a from engagement with the contacts 19 and 19^a after depression of the extension 15^b. After the extension 15^b has been depressed and the plate 16 is held in its 65 tilted position by the action between the contact blades 24 and 24^a and the contacts 19,

19^a as above referred to, the circuit remains closed until it is opened by a subsequent operation, which is effected by placing sufficient pressure on the extension 15^a to move the 70 blades 24 and 24^a from engagement with the contacts 19, 19^a, upon which the spring 25 moves the treadle 15 and plate 16 to substantially parallel relation with the base 10, for 75 which condition ample clearance is provided between the contacts and circuit closing devices of the switch to maintain the circuit through the conductors 21 and 22 in opened condition.

The contact mechanism is preferably 80 enclosed in a housing 26 secured to the base in any suitable manner, for example by screws, to protect said contact mechanism, said housing having an aperture 26^a through its side wall to permit the bar 17 to extend 85 from the plate 16 to the treadle 15.

For convenience the extensions 15^a and 15^b 90 may bear suitable designations or indicating characters for example "M" and "C" to indicate the operation secured by depression of each extension, to-wit momentary application and continuous application.

From the construction described it will 95 appear that my improved switch is of simple construction, that it is substantial throughout, that it effectively protects the operator from electric shock or charge and that no auxiliary devices are employed or required to effect continuous application as distinguished from momentary application and furthermore that the change of position of 100 the foot of the operator required to produce momentary application from that required to produce continuous application is sufficient so that confusion between the two modes of application is readily avoided.

While I have shown my invention in the 105 particular embodiment above described, it will be understood that I do not limit myself to this exact construction as I may employ equivalents known to the art at the time of the filing of this application without departing from the scope of the appended 110 claims.

What I claim is:

1. In a foot switch, the combination of an 115 elongated base of insulating material, a pivotal support carried by each end of said base, the pivot portions of said supports being in alignment with each other, a treadle mounted for oscillation on one of said supports, a plate mounted for oscillation on the other of said supports, metal contact bars carried by said plate, insulated contacts carried by the base for engagement by said bars when said plate is oscillated, and a bar of 120 insulating material rigidly connecting said treadle and said plate, the separation of said treadle and said plate being such as to prevent leakage of high tension current from 125 said contact bars to said treadle.

2. In a foot switch, the combination of an elongated base of insulating material, a pivotal support carried by each end of said base, the pivot portions of said supports being in alignment with each other, a treadle mounted for oscillation on one of said supports, a plate mounted for oscillation on the other of said supports, metal contact bars carried by said plate, insulated contacts carried by the base for engagement by said bars when said plate is oscillated, and a bar of insulating material rigidly connecting said treadle and said plate, one of said contact bars having pivotal connection between its ends with said plate insuring contact between both of its ends and the corresponding ones of said insulated contacts when said plate is oscillated to move said pivoted contact bar against its contacts.
3. In a foot switch, the combination of an elongated base of insulating material, a pivotal support carried by each end of said base, the pivot portions of said supports being in alignment with each other, a treadle mounted for oscillation on one of said supports, a plate mounted for oscillation on the other of said supports, metal contact bars
- carried by said plate, insulated contacts carried by the base for engagement by said bars when said plate is oscillated, and a bar of insulating material rigidly connecting said treadle and said plate.
4. In a foot switch, the combination of an elongated base of insulating material, a pivotal support carried by each end of said base, the pivot portions of said supports being in alignment with each other, a treadle mounted for oscillation on one of said supports, a plate mounted for oscillation on the other of said supports, metal contact bars carried by said plate, insulated contacts carried by the base for engagement by said bars when said plate is oscillated, a bar of insulating material rigidly connecting said treadle and said plate, and a flat spring having one end rigidly secured to said base and its other end engaging said oscillatory structure on opposite sides of its axis of oscillation, whereby oscillating said treadle in either direction depresses the free end of said spring.

In witness whereof, I hereunto subscribe my name this 15th day of May, A. D. 1923.

HECTOR P. MACLAGAN.
